UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

STEERING GEAR FOR ROAD GRADERS.

Application filed December 20, 1924. Serial No. 757,146.

To all whom it may concern:

Be it known that I, FRANKLIN E. ARNDT, a citizen of the United States, residing at Galion, in the county of Crawford and State of Ohio, have invented certain new and useful Improvements in Steering Gears for Road Graders, of which the following is a specification.

This invention relates to steering gears for road graders, and particularly to steering gears of that general type shown in the prior patent #1,166,036, of December 28, 1915, reissued September 5, 1922, #15,443.

In this form of road grader, there is a draft pole and a stub tongue, the draft pole being pivotally mounted upon the front arch of the scraper and having means at its extremity whereby it may be connected to a tractor to thus cause the machine to be drawn along the road. The stub tongue is operatively connected to the front axle so that the front wheels may be manually shifted to any given inclination relative to the main tongue or pole so that, for instance, the tractor may proceed along the middle of a road while the grading machine is being guided to one side of the middle as, for instance, that portion of the road adjacent one of the ditches and be held in this position against side draft and without any tendency of the machine to be drawn out.

In the construction which forms the subject-matter of this previous patent above referred to, the stub tongue is shifted from one side to the other independently of the main tongue or draft pole by means of flexible connections operatively engaging the stub tongue and operated from an operator's station at the rear end of the machine.

The general object of the present invention is to improve upon the construction which forms the subject-matter of said patent and upon devices of the same general character known to me by the provision of means which will cause the more certain and rapid operation of the stub tongue with less strain upon the parts.

A further object is to simplify this construction so as to provide a steering mechanism of this kind which is very simple, which may be readily applied, and which is direct in its action.

A still further object is to provide a construction of this character wherein a wedging action is secured acting to shift the stub

tongue, this wedging action being increased as the strain upon the stub tongue resisting this lateral movement is increased.

Other objects will appear in the course of the following description.

My invention is illustrated in the accompanying drawing, wherein:

Figure 1 is a side elevation of the forward end of a grading machine showing my invention applied to the draft tongue thereof;

Figure 2 is a top plan view of the worm wheel and worm gear, the worm being shown in section and a portion of the pole, the top of the casing being removed;

Figure 3 is a perspective view showing a portion of the axle with one of the collars thereon, one of the braces for the stub tongue, and one of the arch members;

Figure 4 is a perspective view of the slide;

Figure 5 is an elevation of the front axle showing in section the manner of connecting it to the main frame.

Referring to this drawing, and particularly to Figure 1, wherein I have illustrated the forward end of a road working machine constructed in general accordance with my invention, it will be seen that the road scrapping machine includes a forward truck or arch 10 having an axle and a wheel 11. This forward truck is connected by a pintle or king bolt 12 to the forward convergent ends of longitudinally extending supporting arch bars 14 which extend rearward and are at their rear ends supported upon supporting wheels as usual (not shown). Connected to these arch bars in a manner which is not necessary to detail are the draft bars 15, to which the circle on which the scraper supporting bars are mounted is attached for oscillation in a horizontal plane, as usual in constructions of this character. It is not necessary to detail this construction or to illustrate the same, as it forms no part of my invention.

Pivotedly mounted upon the king bolt 13 for oscillation thereon is the draft pole 17, which at its forward end is provided with a clevis 18 by which it may be connected to any suitable draft apparatus as, for instance, a tractor. This draft pole is illustrated as being supported by means of a flexible connection 19 extending upward to a supporting cross piece 20. This construction forms no part of my invention. It will be obvious

that the pole or tongue 17 may swing to right or left and that this will not affect the main axle or arch 10 which is supported by the main axle.

5 Disposed beneath the main tongue or pole 17 is a stub shaft 21, which at its rear end is pivotally connected to a brace 22 which extends from the rear end of the pole or tongue 17 downward and rearward 10 to a point immediately beneath the king bolt 13. The stub tongue 21 is connected to the axle by means of two laterally extending braces 23 which are connected to the stub tongue adjacent its forward horizontal portion and at their rear ends extend beneath the axle. Mounted upon the axle 24 are collars 25, these collars being formed with two upwardly extending passages 26 and a medial passage 27, the lateral passages 26 being surrounded by upstanding bosses 28. Each of these collars is formed in two parts adapted to embrace the axle and be held together by bolts. These bolts pass through the ends of the 15 braces 23.

Rotatably mounted upon the tongue 17 is a downwardly extending shaft 29, the lower end of which carries upon it a crank arm 30. This crank arm at its free end is provided with a vertically extending bearing, and disposed at the free end of the crank arm is a steering block 31 which, as illustrated, has an upwardly extending circular hub 32 which is disposed within the 20 bearing 33 on the end of the crank arm so as to oscillate therein. This block is held in place within the bearing by a nut and bolt 34. This block is formed with a longitudinally extending passage 35 which is 25 rectangular in cross section and has a sliding fit upon the horizontal portion of the stub tongue 21.

Thus it will be obvious that as the crank arm 30 is shifted in one direction or the 30 other from a middle position that the solid block 31 will slide upon the horizontal portion of the stub tongue and that at the same time the stub tongue will be swung from the left, depending upon the direction in which 35 the crank arm 30 is swung. For the purpose of swinging the crank arm, I may use any suitable mechanism but I have illustrated for this purpose the shaft 29 as being provided at its upper end with a worm 40 wheel 36 with which a worm 37 engages, this worm 37 being operatively connected to an operating shaft 38 composed of sections having a universal joint connection to each other. One section of this operating shaft I have designated 38^a, but I have only shown as much of this operating shaft as is necessary for an understanding of my invention and I do not wish to be limited to an operating shaft constructed of sections or to any particular form of operating

shaft, particularly as this operating shaft is practically the same in form as that illustrated in my prior patent above referred to.

As will be seen from Figure 5, the bolster 10 at its ends rests upon a cross bar 39 which is bolted to the upper ends of the collars 25. The braces 10 at their upper ends are connected to a yoke 40 which at its upper end is formed to provide for the support of a member 41 through which the bolt 12 passes and upon which the bolster 42 rests, the member 41 forming part of the bolster. This part 41 is formed with a bore through which the bolt 12 passes, which bore is upwardly and centrally tapered. This construction permits a certain amount of lateral play of these parts.

The operation of this mechanism will be obvious from what has gone before. Normally and when the tractor is directly ahead of the scraper or grader, the stub tongue 21 will be disposed immediately beneath the pole or main tongue 17, but when it is desired to guide and hold the grader to one side of the path of movement of the tractor as, for instance, when the tractor is operating on the crown of the road and the grader is operating at the side of the road, the stub tongue 21 is shifted by means of the crank arm 30 in a direction to hold the stub tongue directly forward, while, of course, the main tongue is swung by the pull of the tractor toward the right or left. This will hold the steering wheels of the grader in such position that the grader will move in a straight line parallel to the side of the road and with the main tongue disposed at an angle to the line of the road and extending to the tractor. Thus the machine is capable of operating at the extreme side of the road, for ditching and the like, while the tractor remains in the middle of the road or even way to one side thereof.

With this steering gear it is possible to 110 operate the grader at an angle of 45° from the engine or tractor and the steering gear is readily operated, there being only a slight turn of the operating shaft required in order to change the direction of the grader. The steering gear enables the operator to 115 guide the grader to either side of the roadway or to work the ditch while the tractor is pulling safely in the middle of the road.

The specific advantages of this particular construction are due to its simplicity and its consequent strength. Furthermore, as the crank arm moves to one side or the other, the block 31 has a sliding action on the crank arm which acts to wedge the crank arm laterally, thus securing very great power. Furthermore, the greater the angle between the stub tongue and the main tongue or pole, the greater this wedging action is, and this is particularly necessary 120

inasmuch as the steering strain reaches its maximum when the tractor is disposed at an angle of about 45° in advance of the grader.

5 I claim:—

1. The combination with a vehicle having a front steering axle and a main tongue pivotally connected to the forward end of the grader for oscillation independent of the 10 axle, of a stub tongue connected to the axle, a crank mounted upon the main tongue, operative connections between the extremity of the crank and the stub tongue whereby to shift the stub tongue to one side or the other 15 as the crank is turned, and manually operable means for shifting said crank.

2. The combination with a vehicle having a front steering axle, a main tongue pivotally connected to the forward end of the 20 vehicle and a stub tongue operatively connected to the axle to shift the latter, of means for manually shifting the stub tongue with relation to the main tongue comprising a crank arm mounted upon the main tongue, 25 a member slidably mounted upon the stub tongue, the extremity of the crank arm being pivotally connected to said member, and manually operable means for oscillating the crank arm.

30 3. The combination with a vehicle having a front steering axle, a tongue operatively pivoted to the forward end of the vehicle and a stub tongue connected to the front axle, of means for shifting the stub tongue 35 into or out of parallel relation to the main tongue comprising a shaft mounted upon the main tongue, a crank arm carried by the shaft, a member slidably mounted upon the stub tongue, a pivotal connection between 40 said member and the extremity of the crank arm, and manually operable means for rotating said shaft.

45 4. The combination with a vehicle having a front steering axle, a tongue operatively pivoted to the forward end of the vehicle and a stub tongue connected to the front axle, of means for shifting the stub tongue 50 into or out of parallel relation to the main tongue comprising a shaft mounted upon the main tongue, a crank arm carried by the shaft, a member slidably mounted upon the stub tongue, a pivotal connection between 55 said member and the extremity of the crank arm, manually operable means for rotating said shaft including a worm gear wheel mounted upon the shaft, and a worm shaft carrying a worm and engaging said worm gear.

60 5. The combination with a vehicle having a front steering axle, a main tongue operatively pivoted to the forward end of the vehicle, a stub tongue, laterally divergent braces connected to the stub tongue and to 65 the axle whereby to cause the unitary movement of the stub tongue and the axle, a

brace mounted upon the main tongue and extending rearward therefrom to which the rear end of the stub tongue is pivotally connected, the point of pivotal connection being in axial alignment with the center of the 70 axle and of the main tongue, the stub tongue having a portion extending parallel to and beneath the main tongue, a crank shaft mounted upon the main tongue, a crank arm carried thereby, a block slidably mounted upon the stub tongue for longitudinal movement thereon, a pivotal connection between the extremity of the crank arm and said block, and means engaging the crank shaft whereby to manually oscillate the crank 75 shaft.

6. The combination with a vehicle having a front arch oscillatably mounted upon the forward end of the vehicle and a front axle carried by the arch and traction wheels 85 thereon, of a main tongue pivotally connected to the arch at the middle thereof, a stub tongue operatively connected to the axle for unitary movement therewith, the stub tongue extending forward and beneath the main tongue, laterally divergent braces connected to the stub tongue and to spaced points on the axle, a brace connected to the rear end of the main tongue extending rearward therefrom and pivotally connected to 90 the rear end of the stub tongue, the point of connection being axially to the pivotal connection of the main tongue to the vehicle and to the arch, a crank shaft mounted upon the main tongue, a crank arm extending 95 therefrom, a block sliding upon the stub tongue, a pivotal connection between the extremity of the crank arm and said block, and manually operable means for shifting 100 the crank shaft to thereby shift the stub tongue.

7. The combination with a vehicle having a front arch oscillatably mounted upon the forward end of the vehicle, a front axle carried by the arch and traction wheels thereon, of a main tongue pivotally connected to the arch at the middle thereof, a stub tongue, the stub tongue extending forward from a point above the axle to and beneath the main tongue, a brace attached to the rear end of the main tongue and extending downward and rearward therefrom, a bar operatively supported upon the axle and extending above the same, the stub tongue and the brace being pivotally connected to the bar on an axis coincident with the axis of the tongue, laterally divergent braces connected to the stub tongue and to spaced points on the axle, a crank shaft mounted upon the main tongue and having sliding engagement at its free end with the stub tongue, and manually operable means for oscillating 115 the crank shaft to thereby shift the stub tongue.

120 8. The combination with a vehicle having a front arch oscillatably mounted upon the forward end of the vehicle, a front axle carried by the arch and traction wheels thereon, of a main tongue pivotally connected to the arch at the middle thereof, a stub tongue, the stub tongue extending forward from a point above the axle to and beneath the main tongue, a brace attached to the rear end of the main tongue and extending downward and rearward therefrom, a bar operatively supported upon the axle and extending above the same, the stub tongue and the brace being pivotally connected to the bar on an axis coincident with the axis of the tongue, laterally divergent braces connected to the stub tongue and to spaced points on the axle, a crank shaft mounted upon the main tongue and having sliding engagement at its free end with the stub tongue, and manually operable means for oscillating 125 the crank shaft.

In testimony whereof I affix my signature.
FRANKLIN E. ARNDT.
